[57] CLAIM

The ornamental design for a trolling motor control, as shown.

DESCRIPTION

FIG. 1 is a front elevational view of a trolling motor control showing my new design;

FIG. 2 is a side elevational view thereof, the opposite side being a mirror image of the illustrated view;

FIG. 3 is a rear elevational view thereof;

FIG. 4 is a top plan view thereof; and

FIG. 5 is a bottom plan view thereof.
